United States Patent Office

Des. 194,811
Patented Mar. 12, 1963

194,811

BOTTLE

George Wesley Worthington, Castro Valley, Calif., assignor to Owens-Illinois Glass Company, a corporation of Ohio

Filed May 17, 1962, Ser. No. 70,183

Term of patent 14 years

(Cl. D58—8)

FIG. 1 is an elevational view of a bottle showing my new design;

FIG. 2 is a top plan view thereof.

I claim:

The ornamental design for a bottle, substantially as shown.
